Primary Examiner — Sheryl Lane

(57) **CLAIM**

The ornamental design for a tarp, as shown and described.

DESCRIPTION

FIG. 1 is an isometric view of tarp showing my new design; FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an exploded top perspective view, with weights removed; and,

FIG. 9 is an exploded bottom perspective view, with fasteners removed.

The broken lines in FIGS. 1, 6, 7, 8, and 9 represent rivets and form no part of the claimed design.

1 Claim, 9 Drawing Sheets**FIG. 1**
